UNITED STATES PATENT OFFICE.

GIUSEPPE MANNINO, OF PHILADELPHIA, PENNSYLVANIA.

DESIGN FOR AN ILLUMINATING DEVICE.

58,496.

Specification for Design.

Patented July 26, 1921.

Application filed December 14, 1920. Serial No. 430,762. Term of patent 7 years.

To all whom it may concern:

Be it known that I, GIUSEPPE MANNINO, a citizen of the United States, residing at Philadelphia, in the county of Philadelphia and State of Pennsylvania, have invented a new, original, and ornamental Design for an Illuminating Device, of which the following is a specification, reference being had to the accompanying drawing, forming a part thereof.

The figure is an elevational view of an illuminating device, showing my new design.

I claim:

The ornamental design for an illuminating device, as shown.

GIUSEPPE MANNINO.
